UNITED STATES PATENT OFFICE.

CHARLES W. HARROLD AND CHARLES J. WRIGHT, OF CLEVELAND, OHIO, ASSIGNEES
TO THE HARRIS AUTOMATIC PRESS COMPANY, OF CLEVELAND, OHIO, A CORPORA-
TION OF OHIO.

PRINTING PRESS.

Application filed April 4, 1922. Serial No. 549,429.

Our invention relates to multi-cylinder, 5 uated scale device for controlling, as well as multi-color printing-presses particularly to planographic or off-set machines, in which the same side of the sheet of paper or stock receives successive impressions from the respective cylinders carrying the separate colors. We have embodied our improvements in a two-color off-set press as shown and hereafter described, but our invention is 10 not to be limited to such type of press.

The primary object of our invention is, among other things, to provide a simplified press of this type with an improved manual or automatic sequential tripping mechanism, 15 so that the tripping on the first printing couple for the first color will automatically control the timing of the trip on the other printing couples for the other colors but so delaying the action of the successive throw-offs until the particular sheet on the several printing units is fully printed with all the colors, combined with means for restoring the impression in the successive printing units in like sequence, and without spoiling 20 any sheet that may be on the press in the separate printing couples.

A further object in the present embodiment is to provide an improved and compact arrangement of cylinders for the two sets of 30 printing couples together with an intermediate transfer-cylinder to pass the sheets from the first set to the second, whereby the form-cylinder in each set is arranged at right angles to its blanket and impression 35 cylinders, with each set tilted at a different angle from the base line of the press to secure proper spacing between the different form and blanket cylinders and also affording convenient access to the various control and actuating mechanisms, while economizing in 40 head-room which has distinct advantages in multi-color cylinder presses of this type for the pressroom of the usual height.

A further object of our invention is to 45 provide an improved mechanism for the two impression cylinders, the intermediate co-acting transfer-cylinder, and the delivery cylinder in operative relation with the second impression-cylinder, by which adjustments of the relative positions of these cylinders to one another may be made to accommodate for printing sheets of varying thickness, with a simultaneous adjustment of the transfer-cylinder in relation to the two 50 impression-cylinders, combined with a grad-

60 A further object of our invention is to provide an automatic relay mechanism combined with the sequential tripping mechanisms of the two sets of printing couples, indirectly 65 controlled either manually or automatically by a feeder trip, by which the throw-off on the second unit is so delayed that the two sheets which are in the machine at the time of the initial tripping in the first unit, are carried completely through the press and printed, before the second throw-off acts, thereby 70 avoiding spoiling any sheet that is in the machine.

A further object of our invention is to 75 provide in connection with the sequential throw-offs for the cylinders of the two units improved mechanism for throwing off the inking form rolls for the form-cylinders of both units so timed in relation to the sequential impression throw-offs as to lift such 80 form-rolls when they are passing over the openings in their respective cylinders so that no portion of the plate will be double inked.

A further object resides in avoiding stopping the press during these sequential trippings for the different cylinders and also the form-rolls in the two sets of printing couples at predetermined points in these respective cycles. By our invention the stopping of the press is unnecessary which saves 90 time in restarting and avoids much loss in production.

Our improved press also presents other features of novelty and usefulness whereby 95 the press is rendered better adapted and more convenient for use in multi-color off-set printing, all of which will be hereinafter set forth and claimed.

The accompanying drawings show a preferred embodiment of our invention in a two-color offset press which is not necessarily restricted to any particular form or type of printing-press construction.

Of the drawings, Fig. 1 is a diagrammatic 105 side elevation of a two couple off-set press adapted for printing twice upon the same side of the sheet. In this figure certain parts shown in other views in detail are omitted, and the various cylinders and form rolls are 110

in normal position with the impression on;

Fig. 2 is an enlarged detail view showing the adjusting mechanism to regulate the positions of certain cylinders, relative to one another, to accommodate sheets of various thickness;

Fig. 3 is an enlarged detail view showing the throw-off mechanism for the first color printing unit, with the trip mechanism to control the operation of the throw-off mechanism, and a portion of the link which connects the throw-off devices for the first unit with the latch in the relay mechanism controlling the operation of the throw-off mechanism for the second color printing unit.

Fig. 4 is an enlarged fragmentary sectional view partly in elevation, showing a form of sheet-controlled trip mechanism which may be used for the throw-off for the first color printing unit;

Fig. 5 is an enlarged detail view showing the throw-off for the first color printing unit set for operation, the mechanism therefore being positioned by the sheet-trip mechanism or manually by the operator;

Fig. 6 is a view similar to Fig. 5 showing the blanket-cylinder of the first color unit separated from its impression-cylinder which action sets the latch to throw-off the impression in the second color unit;

Fig. 7 is an enlarged detail view showing the latch in the relay mechanism for the throw-off mechanism for the second color printing unit, the parts being in normal position with the impression on;

Fig. 8 is a detail view showing the latch for controlling the operation of the throw-off mechanism for the second color printing unit, this view showing the latch while idling;

Fig. 9 is a detail view showing the cam-plate for moving the pawl of the latch shown in Fig. 8, as moved into position to lift this latch pawl into alignment with the pin on the releasable catch normally preventing the throw-off mechanism from shifting into operative position for engagement with an actuating element to throw-off the impression for the second color printing couple; this cam-plate is moved into the position shown by a link connected with the throw-off mechanism for the first color printing unit;

Fig. 10 is an enlarged detail view showing the throw-off mechanism for the second color printing unit about to be positioned to operate the compound toggle devices to move the blanket cylinder of this second unit away from its coating form and impression cylinders; in this figure the latch pawl frame, or carrier, is shown as having been actuated by its cam-plate to release the catch which allows the throw-off mechanism for the second color unit to come into operative position;

Fig. 11 is an enlarged view showing a po-

sition for the throw-off mechanism of the second blanket-cylinder and its connection with said cylinder together with the inker throw-off mechanism;

Fig. 12 is an enlarged detail view showing the throw-off mechanism for the second blanket-cylinder as having been operated upon by its actuating cam on the second impression-cylinder.

Figs. 13 to 16 inclusive are enlarged detail views showing the structure and relation of the different parts comprising the controlling latch relay mechanism for the throw-off mechanism for the second color printing unit; and

Fig. 17 is an enlarged detail face view showing the throw-off ratchet mechanism for the form-rolls for inking the two form-cylinders.

Similar numerals refer to similar parts throughout the several figures.

Referring particularly to Fig. 1, the frame 18 supports a series of eight cylinders all of equal diameter comprising the two printing units each comprising an off-set printing set

of three cylinders, the first unit passing the successive sheets to the second unit by a transfer cylinder intermediate the two impression cylinders, and the second impression cylinder coacting with a delivery-cylinder to carry the sheets to any suitable delivery mechanism. The form-cylinder 19 of the first unit is mounted on the shaft 20 journaled in the frame 18, the cylinder 19 coacting with the blanket-cylinder 21 which coacts with the impression-cylinder 22, these two cylinders being mounted on the shafts 23 and 24 respectively. The second color unit comprises the form-cylinder 25, the blanket-cylinder 26 and the impression-cylinder 27 all mounted on the shafts 28, 29 and 30 respectively which are suitably journaled in the frame 18. Between the two impression-cylinders 22 and 27 is the transfer-cylinder 31 mounted on the shaft 32 and adapted to carry the successive sheets from the cylinder 22 to the cylinder 27. Below the impression-cylinder 27 is the delivery-cylinder 33 mounted on the shaft 34 by which the printed sheets are taken from the cylinder 27 and transferred to a delivery mechanism (not shown).

The arrangement of the separate sets of cylinders in the two units is such that the form-cylinder 19 is disposed at right angles to the blanket-cylinder 21 and impression-cylinder 22, and in like manner the form-cylinder 25 of the second unit is arranged at right angles to the blanket-cylinder 26 and impression-cylinder 27. Furthermore the two sets of cylinders comprising each unit are arranged to be tilted at different angles to the base line of the press, such arrangement providing a horizontal space for a passage-way for the pressman resting

in the frame 18 between the two form-cylinders 19 and 25 from which he may conveniently regulate the ink and water fountains for the two form-cylinders from the same 5 position, while also having access to the blanket-cylinder 21 to touch up or sponge off same according to requirements, while the blanket-cylinder 26 may also be conveniently reached from the floor for similar 10 manipulations at the left end of the press as shown in Fig. 1. Again the arrangement of the eight cylinders in the frame 18 relatively to each other to constitute the two-color off-set press shown in the drawings 15 affords a maximum accessibility to the cylinders requiring inspection or manipulation with great efficiency in action as well as economy in space occupied.

The respective cylinders have each 20 fastened thereto suitable gears the pitch-diameters of which coincide with the peripheries of the respective cylinders. These gears intermesh and form the driving mechanism to secure the proper rotation of all 25 eight cylinders in the directions shown by the arrows on the different cylinders in Fig. 1. Power is derived from any suitable source which is connected to the cylinder gears by a compound gear train. Since 30 these are common forms of printing-press construction and are well-known in the art, they are not shown in detail in the drawings.

The shaft 23 carrying the blanket-cylinder 21 is mounted at both ends in the eccentric 35 bearings 35 which in turn are mounted in the journals 36 affixed to the frame 18; in like manner the shaft 29 carrying the second blanket-cylinder 26 is mounted in eccentric bearings 37 carried by journals 38. The 40 shaft 24 for the first-impression-cylinder 22 is mounted at both ends in eccentric bearings 39 secured in journals 40; also the shaft 30 for the second impression-cylinder 27 is mounted in eccentric bearings 41 secured in 45 journals 42. The shaft 32 for the intermediate transfer-cylinder 31 is in like manner mounted at both ends in eccentric bearings 43 secured in journals 44 affixed to the frame 18, and the shaft 34 of the delivery-cylinder 50 33 is also mounted at both ends in eccentric bearings 45 secured in journals 46 secured to the frame 18.

The inking mechanisms for the two form-cylinders 19 and 25 are duplicates in construction and operation, and only one set of such inking rolls with means to raise same from the respective form-cylinders is shown in connection with the second form-cylinder 25, the inking mechanism for the 55 first form-cylinder 19 not being shown: The inking rolls 47 are mounted on transverse shafts 48 carried in slotted bearings (not shown) in the frame 18. The end of each shaft 48 forms a cylindrical bearing adapted 60 to be engaged by rollers 49 mounted on two

rock-arms 50 and 51 pivotally secured to studs 52 and 53 respectively. The inner ends of the arms 50 and 51 are operatively connected by links 54 and 55 respectively to the bell-lever 56 pinned at 57 to the frame 70 18. The arm 58 of the lever 56 is connected by the link 59 to the inker throw-off mechanism hereinafter to be more particularly described. When the link 59 is lowered the inking rolls 47 are lifted from their respective form-cylinders 19 and 25, and when the link 59 is raised such inking rolls 47 are restored into contact with the form cylinders 75 19 and 25.

The automatic throw-off and throw-on mechanisms for the two blanket-cylinders 21 and 26 are identical in construction and operation to secure the sequential tripping of the two printing color units and are best shown in Figs. 3, 5 and 6, and it will only 80 be necessary to describe the detailed structure and operation of one of these mechanisms, whereby the blanket-cylinder is moved from and to both its form and impression-cylinders, actuated either manually 85 or automatically by the feeder trip controlled by the interruption or absence of stock in the feed supply. Referring to Fig. 3, the impression-cylinder shafts 24 and 30 carry the cam 60 which engages the roller 61 on the lever arm 62 pivoted on the stud 63 in the bracket 64 secured to the frame 18. The lug 65 on the lever-arm 62 slidably carries the rod 66 about which is coiled the spring 67 which acts to hold the roller 61 in engagement with the periphery of the cam 60. The lower end of the rod 66 is pivotally secured to the bracket 64 by the pin 68. The lever-arm 62 also carries the depending bracket 69 which is pivotally connected by 90 the link 70 to the depending arm 71 projecting downwardly from the bell-crank lever 72 pivoted to the stud 63. The arm 71 also carries the lug 73 through which the rod 74 slidably passes with its inner end pivotally 95 secured to the pin 68 with the spring 75 coiled about the rod 74 normally to hold the arm 71 under tension in the position shown in Fig. 3. The bracket 69 slidably supports the rod 76 with its lower end 77 100 projecting below the bracket 69, the length of this end 77 being regulated by adjusting units 78. Pivotally secured to the stud 79 is the rock-arm 80 carrying the shoulder 81 faced with a hardened plate and adapted to 105 be engaged by the rod-end 77 as shown in Fig. 6. Adjacent the stud 79 is the stud 82 upon which is pivotally mounted the bell-crank lever 83 which carries the shoulder 84 of similar construction and function as the shoulder 81, Fig. 3 showing the shoulder 84 in operative alignment with the rod-end 77 after having been engaged thereby. The lower arm 85 of the lever 83 is 110 connected by the link 86 to the arm 80. The 115

4 arms 80 and 85 carry adjustable pins 87 and 88 respectively which are adapted to engage with the stop-pin 89 to limit the movements of the arms 80 and 85 respectively as shown in Figs. 3 and 6. The upper arm 90 of the lever 83 forms a toggle lever with the toggle link 91, the toggles being pinned at 92. It will be noted that the arms 80 and 85 as they are rocked on their respective studs 79 and 82 are maintained in substantial parallelism by the link 86. The toggle link 91 is pivotally secured to the bell-lever 93 mounted on the stub-shaft 94 affixed to the frame 18 and the arm 95 of the lever 93 is pinned at 96 to the toggle lever 97 which is pivotally secured to the arm 98 affixed to the eccentric bearings 35 and 37 of the two blanket-cylinders 21 and 26. The adjustable screw-bolt 99 in the lever 97 regulates its length to control the throw of such eccentric bearings in the proper operation of the toggle 95, 97.

When the rod-end 77 is shifted to the right as shown in Fig. 5, and then pressed down on the shoulder 81 by the cam 60, as shown in Fig. 6, the arm 80 is swung in an anti-clockwise direction which straightens the toggle levers 90 and 91 and simultaneously breaks the toggle levers 95 and 97 connected with the arm 98 carried by the eccentric bearings 35 and 37 to throw-off the impression by separating the blanket-cylinder from both its form and impression cylinders as shown in Fig. 6. The impression is restored when the rod-end 77 is swung to the left by the spring 75 and pressed down thereafter on the shoulder 84 by the action of the cam 60 to swing the arm 85 in an anti-clockwise direction to break the toggle levers 90 and 91 and straighten the toggle levers 95 and 97 thereby moving the eccentric bearings 35 and 37 to restore the blanket-cylinders 21 and 26 to printing relation, as shown in Figs. 3 and 5.

45 Automatic means are provided to raise the inking rolls 47 from their respective form-cylinders 19 and 25 in predetermined sequence with the throwing off of the impression by separating the blanket cylinders from both their respective form and impression cylinders. Such inker throw-off is preferably actuated when the inking rolls 47 are about to pass over the opening in the form or plate cylinders after the impression is thrown off which may advantageously occur at a fixed point when the gaps of the several cylinders in each unit (form, blanket and impression) are adjacent one another. The improved mechanisms for lowering the rod 59 to throw-off the inking rolls 47 is the same in both units, and only one set will be described. Such mechanism is best shown in Figs. 1, 3, 5, 6, 11, and 17: Referring more particularly to Figs. 3, 5 and 6, the impression-cylinder shafts 24 and 30

carry the cam 100 which may be adjustably mounted (by means not shown) on the two shafts so that the action of this cam 100 may be variably adjusted in predetermined sequence to the action of the impression throw-off cam 60 to alter the respective timings of the two throw-offs in each unit as may be desired. In the embodiment shown, this inker throw-off cam 100 does not operate until about two-thirds of a rotation of the impression cylinders after the impression has been tripped by the cam 60, as shown in Fig. 6. Mounted on the stub-shaft 101 is the rock-lever 102 carrying the cam-roller 103 pivoted on the pin 104, the roller 103 being adapted to be engaged by the cam 100 at predetermined points in the cycle when the lever 102 is rocked to bring the roller 103 into the path of such cam. Pivotally secured to the pin 96 is the arm 105 having formed in its extremity the recessed shoulder 106 which rests on the pin 104. The under side of the arm 105 has the cam-recess 106^a cut therein which rides over the roller 107 journalled in the stud 108 secured to the frame 18 when the toggle levers 95 and 97 are straightened in the position shown in Figs. 3 and 5. When this toggle is broken as shown in Fig. 6, the arm 105 rocks the lever 102 on its stub-shaft 101 in an anti-clockwise direction and pushes the cam-roller 103 into the dotted line position shown in Fig. 6, the arm 105 being raised out of engagement with the pin 104 by its sliding out of the cam-recess 106^a over the roller 107 thereby releasing rock-lever 102 from operative engagement with the arm 105. Referring to Figs. 11 and 17, the arm 109 of the rock-lever 102 forms a toggle with the toggle link 110 pinned together by the pin 111. The link 110 is pivotally secured to the rock-arm 112 rotatably mounted on the sleeve 113 journalled on the stub shaft 114 affixed to the frame 18; also affixed to the sleeve 113 is the ratchet 115 the teeth of which are adapted to be engaged by the pawl 116 pivotally secured to the rock-arm 112. Journalled on the sleeve 113 is the bracket 117 carrying at either end the oppositely-disposed pawls 118 and 119 to engage the ratchet 115 as shown in Fig. 17. Also affixed to the sleeve 113 is the rock-arm 120 pivotally secured to the rod 59 and the hand-lever 121 is also secured to this sleeve 113 as shown in Figs. 1 and 7. The pawls 116, 118 and 119 are each held in engagement with the ratchet 115 by springs 112, 123 and 124 respectively mounted on supporting studs 125, 126 and 127 to bear on pins 128, 129 and 130 respectively as shown in Fig. 17. When the toggle levers 109, 110 are broken in the direction as shown in dotted lines in Fig. 17, the pawl 116 is lowered into engagement with a tooth in the ratchet 115; thereafter when the cam 100 revolves to the 130

dotted line position shown in Fig. 6 the rock-lever 102 is moved from its dotted line position to the full line position shown in Fig. 6, because the arm 105 has been theretofore lifted and released from the pin 104 as hereinbefore described. This oscillation of the rock-lever 102 by the action of the cam 100 again straightens the toggle levers 109, 110 which in turn swing the pawl 116 in engagement with the ratchet 115 to rock the sleeve 113 in an anti-clockwise direction which depresses the arm 120 secured to the sleeve 113, thereby lowering the rod 59 to throw-off the inking-rolls 47 from their respective form-cylinders 19 and 25. When the hand-lever 121 is raised the ratchet 115 is also revolved in the same direction by the pawl 118 to throw-off the inkers, while an opposite downward movement of this hand-lever 121 will cause the pawl 119 to engage the ratchet 115 to rotate the latter in a clockwise direction to restore the inking-rolls 47 to operative contact with the form-cylinders 19 and 25. By these devices the inkers may be thrown off either manually or automatically and in timed sequence with the impression throw-off in each printing unit through the continued movement of the press, while the separate inkers are restored to operative relation by the manual means after the impression has been restored.

In order that the impression throw-off mechanism in the first printing unit, thereafter sequentially tripping its inker throw-off, may be automatically actuated in case of the failure of the feed of a sheet to the press, the following mechanism has been devised for such purpose: The feed table 131 is secured to the frame 18 in any suitable manner, over which table the sheets are successively advanced to the impression-cylinder 22 as shown in Figs. 3 and 5. Extending transversely in the frame 18 is the spring-impelled throw-off shaft 132 which is oscillated by the spring 133 coiled about this shaft the inner end being pinned to the collar 134 secured to the shaft 132 as shown in Fig. 4. The shaft 132 carries the arm 135 connected by the link 136 to the rock-lever 137 journalled in the stub-shaft 138 secured to the frame 18. The rock-lever 137 has the rod 139 pivotally secured thereto, the lower end of this rod slidably mounted in the lug 140 affixed to the arm 72. Coiled about the rod 139 and between the lug 140 and the adjusting nuts 141 screw-threaded on the rod 139 is the coil spring 142 normally tending to push the rod 139 upwardly in the direction shown by the arrow in Fig. 3. When the shaft 132 is oscillated under the force of the spring 133 (aided somewhat by the spring 142) in a clockwise direction the link 136 is depressed to shift the rock-lever 137 to the position shown in Fig. 5 to swing the arm 72 about the stud 63

whereby the positions of the bracket 69 and rod-end 77 are moved from the positions shown in Fig. 3 to those shown in Fig. 5 thereafter to operate the impression throw-off devices of the first printing unit here-
fore described to throw the blanket-cylinder 21 off impression. The hand-lever 143 is operatively connected to the shaft 132 either to throw-off the impression or to throw-on the impression and reset the latch-trip mechanism now to be described.

The shaft 132 is held in the position shown in Fig. 3 by the latch 144 pivoted on the shaft 145 journalled in the frame 18 and extending across the feed-table 131 as shown in Fig. 4. The latch 144 engages with the notch 146 cut in the collar 147 secured to the shaft 132. Preferably this latch 144 is released automatically through trip mechanism on the feeder: The feed table 132 supports the stock 148 that is being fed to the press. Extending transversely above the feed-table 131 and journalled in uprights at the sides thereof is the shaft 149 which carries the arm 150 (Figs. 3 and 5) connected by the rod 151 to the impression-cylinder shaft 24 by means of the pin 152 so as to impart to the shaft 149 an oscillating movement. 153, 153 are spaced-apart grooved collars rigidly secured to the shaft 149. Adjacent each collar 153 is the disk 154 affixed to the inner end of the tubular shaft 155 which is loosely sleeved on, and encloses a portion of, the shaft 149, as shown in Fig. 4. The tubular shaft 155 carries the arm 156 having a projecting lug 157 which engages with the arm 158 secured to the shaft 145. The trip-lever 159 is pivotally secured at 160 between the parallel sides of the grooved collars 153 so that its longer and heavier arm is held from falling into the aperture 161 cut in the top of the feed table 131, by the interposition of the stock 148 as shown in Figs. 3 and 4. The opposite end of the trip-lever 159 is T-shaped to form the laterally extending tooth 162; in the peripheries of the collars 153 and also of the disk 154 are formed cut-outs 163 and 164 respectively. Ordinarily the tooth 162 rests against, or is in proximity to, the periphery of the disk 154; it can engage with the cut-out 163 of the collars 153 only when it can fall into the cut-out 164 of the disk 154. When this occurs the disk 154 with its tubular shaft 155, which is normally at rest, are locked to and turn with the oscillating shaft 149 as shown in Fig. 5. The entrance of this tooth 162 into locking engagement with the disk 154 will occur upon the failure or interruption in the feed supply. When the stock 148 is in proper position, as shown in Figs. 3 and 4, the curved longer arm of the trip-lever 159 will engage therewith and will be prevented from lowering into the aperture 161, and

100
90
95
105
110
115
120
125
130

from turning sufficiently to interlock with the disk 154. If the stock 148 should, at any time, be interrupted or absent, the longer arm of the trip-lever 159 will fall of its own weight into the aperture 161, thereby causing the tooth 162 to interlock with the cut-out 164 in the disk 154. Thus the tubular shaft 155 will be caused to oscillate with the shaft 149 to release the latch 144 10 engaging the notch 146 in the collar 147 on the shaft 132. Through this movement of this herein described mechanism, the shaft 132 is partially rotated by the spring 133 in a clockwise direction as shown by the arrows in Figs. 3 and 5 to throw-off the impression by separating the blanket-cylinder 21 from both the form-cylinder 19 and impression-cylinder 22 in the first printing unit, as shown in Fig. 6, all controlled automatically by the stock.

Means are provided to control and position the throw-off mechanism for the blanket-cylinder 23 in the second unit, and also the inker throw-off of such second printing unit in predetermined sequence with the respective throw-offs for the first printing unit, controlled, but not operated, by the impression throw-off mechanism of the first printing unit: Referring particularly to Figs. 7, 8, 9 and 10, we have devised a latch relay mechanism for the impression throw-off of the second printing unit which is described as follows: The stub-shaft 165 is secured to the frame 18 and has sleeved thereon the tubular bracket 166 arranged between the oscillated collar 167 and the washer 168 held in place by the pin 169 as shown in Fig. 15; journalled on the bracket 166 and held in place by the washer 168 is the sleeve 170 on which is mounted the rock-lever 171. The upper arm 172 of the lever 171 carries the cam-roller 173 journalled on the pin 174 passing through the sleeve 175 affixed to the lever-arm 172 and is disposed in the path of the cam 60 mounted on the impression-cylinder shaft 30 as shown in Fig. 10. The lower arm 176 of the lever 171 carries the adjustable pin 177 adapted to engage the stop 178 mounted on the stub-shaft 179 affixed to the frame 18, as shown in Fig. 14. The pin 174 has pivotally secured thereto the latch 180 extending rearwardly or to the right as shown in Figs. 9, 10 and 13, with a concave end 181 adapted to engage with the pin 182 projecting laterally from the upright catch arm 183 mounted on the collar 184 journalled on the shaft 179. The arm 183 has a notch 185 formed therein adapted to rest on the lug 186 projecting from the block 187 on the bracket 166 when the catch arm 183 is in normal position as shown in Figs. 9 and 13. Secured to the upper face of the collar 167 is the cam-plate 188 which is oscillated by the rock-arm 189 secured to the under side of the collar 167. The arm 189

is connected to the impression throw-off mechanism of the first printing unit by the rod 190 the rear end of which is adjustably secured to the lug 191 on the toggle lever 90 by nuts 192 as shown in Figs 3, 5 and 6. 70 Referring more particularly to Figs. 13 and 14 the block 187 on the bracket 166 carries on its upper end the short shaft 193. The inner end of the shaft 193 carries the swinging pawl 194 having the pin 195 projecting inwardly from this pawl to ride over the cam-plate 188; the latch 180 is held in engagement in the pin 195 by the coil-spring 196 between the arm 172 and latch 180. The outer end of the shaft 193 pivotally 80 carries the rod 197 the lower end of which is slidably mounted in the lug 198 on the end of the arm 72 as shown in Figs. 7 and 10. Coiled about the rod 197 and between the lug 198 and the adjusting nuts 199 85 screw-threaded on the rod 197 is the coil spring 200 which normally tends to push the rod 197 upwardly and to the left in Fig. 10, but is held from this movement by the catch-arm 183 resting on the lug 186 as shown in Fig. 13. The spring 201 connects the catch-arm 183 with the lug 202 on the rock-arm 176 to hold the former in engagement with the lug 186 as well as hold the rock-lever 171 so that the pin 177 is in engagement with the stop 178 with the cam-roller 173 projecting to the left in the path of the cam 60 as shown in Figs. 7 and 9. The cam-roller 173 is engaged by the cam 60 in each cycle as shown in Figs. 8 and 10 90 thereby oscillating the rock-lever 171 in a clockwise direction to inaugurate the action of the impression throw-off mechanism of the second unit, but only when the rod 190 has been pushed to the left (Fig. 10). When the rock-arm 189 is in the position shown in Fig. 8, latch relay mechanism is idling with the latch 180 dropping over the pin 195 and below and out of range of the pin 182 on the catch-arm 183. However when the arm 189 has been shifted by the rod 190 to the positions shown in Figs. 9, 10, the cam-plate 188 simultaneously raises the pawl 194 and its pin 195 lifts the latch 180 so that its end 181 will engage the pin 182 on the catch 183, when the cam 60 thereafter engages the cam-roller 173 to force the latch 180 to the right as indicated by the arrows in Fig. 10. When the catch 110 183 is thus forced off the lug 186 on the block 187, the bracket 166 is free to oscillate in an anti-clockwise direction on the shaft 165 by the action of the coil-spring 75, which shifts the impression throw-off mechanism to the dotted line position shown in Fig. 10 with the rod-end 77 swung to the right as indicated by the arrow in a position to depress the shoulder 81 when the cam 60 has thereafter revolved to act thereon by engaging the cam-roller 61 to actuate 120 125 130

the throw-off mechanisms to separate the blanket-cylinder 26 from both cylinders 25 and 27, as indicated by the arrows in Fig. 11, the dotted line showing the position of the cylinder 26 when the impression is on, while the dash and dot line shows the cylinder 26 separated or off impression.

The impression is automatically restored in the second unit by the movement of the 10 rod 190 to the right which shifts the cam-plate 188 back to its normal left position thereby lowering the nose of the pawl 194 into the path of the lug 172^a on the arm 172.

At the next actuation of the cam-roller 173 15 by the cam 60, the bracket 166 will be rocked so as to force the rod 197 downwardly to position the impression throw-off mechanism as shown in Fig. 7, and also to lower the lug 186 to reset the catch 183.

20 Means are provided for separately adjusting the position of the two impression cylinders 22 and 27 with relation to their respective blanket-cylinders 21 and 26, and also the relation of the transfer-cylinder 31

25 with respect to the two impression-cylinders 22 and 27 to variably adjust their relative positions so as to accommodate stock of varying thickness, all while the press is in operation. Such means are each preferably

30 combined with a graduated scale to serve as an accurate indicator to enable the separate adjustments to be uniform throughout according to the thickness of the particular stock that is being fed to the press. The

35 mechanism for accomplishing this feature of our improvement is shown in Fig. 1 and partly in detail in Fig. 2. As such devices are the same for all three cylinders 22, 27 and 31, a single description of the attach- 100

40 ment for one cylinder will suffice. Referring to Fig. 2 the eccentric bearing 39 of the impression-cylinder 22 (for example) carries the arm 203 to which is pivoted the rod 204 adjustably secured to the bracket 205

45 by the adjusting units 206. The lower end of the bracket 205 is formed with journal 207 to contain the eccentric bearing 208 mounted on the stub-shaft 209 secured to the frame 18. The eccentric bearing 208 is

50 moved on the shaft 209 within the journal 207 to swing the bracket 205 by the arm 210 secured to such bearing 208; the arm 210 carries the screw-threaded lug 211 engaged by the screw-threaded micrometer rod 212

55 rotatably supported by the bracket 213 se- cured to the frame 18, and actuated by the handle 214. The lug 211 also carries a graduated scale 215 arranged in proximity to the tip of the micrometer rod 212 to in- 105

60 dicate the extent of the adjustment. The screw bolt 216 maintains the rod 212 in any predetermined position in the lug 211 after adjustment. When the arm 210 is raised or lowered by the rotation of the rod 212, the

65 eccentric bearing 39 is slightly shifted so

that the position of the cylinder 22 with relation to the blanket-cylinder 21 is changed to properly accommodate the thickness of the stock to be fed to the press. For example, if the press has been set for 70 .040 inch cardboard, and it is afterwards desired to feed stock only .010 inch in thickness, each impression-cylinder is adjusted .030 inch towards its blanket-cylinder, after which the transfer-cylinder 31 is re-adjusted 75 to the two impression cylinders by a single movement of this cylinder 31 as the latter follows a median line formed by the contact of all three cylinders 22, 27 and 31 in their various positions. The delivery-cylinder 33 is also provided with similar adjusting means with reference to the impression-cylinder 27 by shifting the eccentric bearings 45 for this cylinder by a slotted lever 217 journalled in the stub-shaft 218 to raise 80 or lower the rod 204 as heretofore described. The bolt 219 with wing-nut 220 extending through the slot 221 in the lever 217 locks the latter in any desired position. No mi- 85 crometer attachment is necessary for this 90 delivery-cylinder 33, as a close and accurate adjustment is unnecessary in taking the printed stock from the second impression-cylinder 27.

The operation of the hereinbefore de- 95 scribed mechanism in the two-color off-set press shown in drawings as a preferred em- bodiment is substantially as follows: When- ever the stock 148 is interrupted or is ab- 100 sent from the feed-table 131, the trip-lever 159 acts to release the spring-impelled shaft 132 so that the rock-lever 137 is shifted from the position shown in Fig. 3 to that shown in Fig. 5, the rod 139 being moved in the direc- 105 tion of the arrow in Fig. 3. This movement shifts the bracket 69 and rod-end 77 so that the latter will engage the shoulder 81 when depressed by the cam 60 carried by the im- 110 pression-cylinder shaft 24. Fig. 3 shows the cam-roller 61 about to ride on the high part of the cam 60 while Fig. 6 shows the rod- 115 end 77 as having swung the arm 80 to oper- ate the toggles 90, 91 and 95, 97 to shift the eccentric bearings 35 to separate the 120 blanket-cylinder 21 from both its form-cyl- 125 130 inder 19 and impression-cylinder 22. As the toggle levers 95 and 97 are being broken, the arm 105 rocks the lever 102 to bring the cam-roller 103 into the path of the form- roll cam 100 to throw-off the inking rolls 47 by the intermediate mechanism hereto- fore described. In like manner when the toggles 90, 91 are straightened as shown in Fig. 6, the rod 190 is thereby forced to the left as indicated by the arrows in Figs. 9 and 10, to actuate the latch relay devices heretofore described to release the catch- arm 183 to allow the rod 197 to be moved to the left by the spring 75 in the second printing unit after the cam-roller 173 has

been moved to the right from the position shown in Fig. 7 to that shown in Figs. 8 and 10 by the cam 60 to shift the rod-end 77 from the full line position shown in Fig. 5 10 to the dotted line position indicated by the arrow so that the cam 60 on completing its revolution as shown in Figs. 11 and 12 may depress the cam-roller 61 to separate the blanket-cylinder 26 from both its form-cylinder 25 and impression-cylinder 27, the toggle-levers 95 and 97 in being broken from Fig. 11 to Fig. 12 moving the arm 105 in the second unit to position the inker throw-off devices by bringing the cam-roller 15 103 into the path of the cam 100 on the impression-cylinder shaft 30 to operate this inker throw-off in timed sequence with the impression throw-off as in the first printing unit.

20 In both units the sequential trippings of the impression throw-off and the inker throw-off preferably occur at a fixed point, the impression throw-off occurring when the gaps of the three cylinders are adjacent one 25 another, while the inker throw-off operates to raise the form-rolls when the latter are about to pass over the opening in the respective form or plate-cylinders. The throw-off of the impression for the first unit may 30 also be operated manually by pressing down on the hand lever 143 which releases the latch 144 to allow the shaft 132 to oscillate to inaugurate the sequential tripping throughout both units. As shown in Fig. 3 35 with the impression on, the latch pawl 144 is held in the notch 146 by the constant downward pull exerted on the arm 135 by the springs 67 and 75. When the operator presses down on the hand lever 143 to relieve the pressure of the notch 146 in the 40 collar 147 on the latch pawl 144, the weight of the depending arm 158 which hangs at an angle from the vertical (Fig. 3) will swing the pawl 144 to the right and thereby 45 swing the pawl 144 to the right and thereby clears the notch 146, so as to allow the spring-impelled shaft 132 to oscillate to throw off the impression when the operator lets go of the hand lever 143. The throw-off timings of the two units are so delayed, 50 one with the other, that each of the two sheets which are in the machine at the time of the initial tripping in the first unit is carried completely through the press and printed, the throw-offs in the second unit not 55 acting until the sheet in the first unit has passed through the second unit, thereby preventing any sheet already properly fed to and in the press from being spoiled, all of which throw-offs will advantageously occur 60 while the press is in operation.

In like manner the impression for the two units may be restored in like sequence in the continued operation of the press, after the hand-lever 143 resets the latch 144 and 65 shifts the rock-lever 137 in the first unit to

swing the rod-end 77 upwardly in Fig. 3 so as to coact with the shoulder 84 to allow the cam 60 to operate the toggles 90, 91 and 95, 97 to restore impression, the breaking of the toggle 90, 91 simultaneously moving the 70 rod 190 to the right to bring the latch relay mechanism to the position shown in Fig. 7. This movement permits the cam 60 of the second unit to restore the impression in this unit in the same manner as heretofore described for the second unit. The inking-rolls 47 of the two units are restored to operative position on the form-cylinders 19 and 25 by raising the hand-levers 121 which straightens the toggles 109, 110 and rocks 80 the levers 102 to carry the cam-rollers 103 out of the path of the cams 100 whereby the pins 104 again engage the shoulders 106 of the arms 105.

The foregoing constructions embody the 85 principles of our invention as applied to a two-color offset printing-press, but our invention is also applicable to other forms of printing-presses and printing more than two colors and other embodiments and modes of operation may be made. However the foregoing is sufficient to disclose the underlying principles and advantages involved.

We claim as our invention:—

1. In a multicolor press, a plurality of 95 printing couples each having independent normally inoperative means for separating the couple, and a normally disconnected latch relay mechanism positively controlled and simultaneously actuated by the tripping movement of one of said couple separating means for placing in operative position at a predetermined point in the cycle another 100 of said separating means.

2. In a multicolor press, a plurality of 105 printing couples each having independent normally inoperative means for separating the couple, and means positively controlled and directly actuated by the tripping movement of one of said couple separating means for simultaneously positioning a part of an adjacent couple-separating means for subsequent actuation at a predetermined point in the cycle. 110

3. In a multicolor press, a plurality of 115 printing couples each having independent normally inoperative means for separating the couple, and means positively controlled and directly and simultaneously actuated by the tripping movement of one of said couple separating means for simultaneously positioning a part of an adjacent couple-separating means for subsequent actuation at a predetermined point in the cycle operable 120 through continued movement of the press.

4. In a multicolor press, a plurality of 125 printing couples, normally inoperative means for throwing off impression for the first couple, independent normally inoperative means for throwing off impression for an- 130

other couple, and timing means positively controlled and directly actuated by the tripping movement of said first impression throw-off means for simultaneously positioning a part of said other impression throw-off means in operative position to be directly actuated in predetermined sequence by an element carried by said second couple actuated through continued movement of the press.

5. In a multicolor press, a plurality of printing couples, each comprising a pair of rotary printing members, normally inoperative means for throwing off impression for the first couple, independent normally inoperative means for throwing off impression for another couple, and timing means comprising a latch relay mechanism positively controlled and directly actuated by the tripping movement of said first impression throw-off means for simultaneously positioning a part of said other impression throw-off means in operative position to be directly actuated in predetermined sequence by an element carried by one of the printing members of said second couple actuated through continued movement of the press.

6. In a multicolor press, a plurality of printing couples, each comprising a pair of rotary printing members, normally inoperative means for throwing off impression for the first couple at a predetermined point in the cycle, independent normally inoperative means for throwing off impression for another couple, and timing means comprising a latch relay mechanism positively controlled and directly actuated by the tripping movement of said first impression throw-off means for simultaneously positioning a part of said other impression throw-off means in operative position to be directly actuated in predetermined sequence in its cycle by an element carried by one of the printing members of said second couple actuated through continued movement of the press.

7. In a multicolor press, a plurality of printing couples, independent normally inoperative means for throwing off impression in each couple, means for actuating said throw-off means in one couple, a normally disconnected timing mechanism positively controlled and simultaneously operated by the tripping movement of said last mentioned means for simultaneously positioning a part of the impression throw-off means of the next couple, and means carried by said next couple for thereafter actuating its throw-off means, all of said throw-offs being normally disconnected but sequentially operable through the continued movement of the press.

8. In a multicolor press, a plurality of printing couples, independent normally inoperative means for throwing off impression in each couple, means for actuating said

throw-off means in one couple, a normally disconnected timing mechanism comprising a latch relay mechanism positively controlled and simultaneously operated by the tripping movement of said last mentioned means for simultaneously positioning a part of the impression throw-off means of the next couple, and means carried by said next couple for thereafter actuating its throw-off means, all of said throw-offs being normally disconnected but sequentially operable at variably predetermined points in each cycle through the continued movement of the press.

9. In a multicolor offset press comprising two printing units each composed of a form-cylinder, a blanket-cylinder and an impression-cylinder, separate normally inoperative means for separating the blanket-cylinder from both form and impression-cylinders in each unit, and a timing mechanism positively controlled and simultaneously actuated by the direct movement of the separating means in the first unit to simultaneously place a part of the then normally inoperative separating means in the second unit in operative position.

10. In a multicolor offset press comprising two printing units each composed of a form-cylinder, a blanket-cylinder and an impression-cylinder, separate normally inoperative means for separating the blanket-cylinder from both form and impression-cylinders in each unit, and a timing mechanism positively controlled and simultaneously actuated by the direct movement of the separating means in the first unit to simultaneously place a part of the then normally inoperative separating means in the second unit in operative position for subsequent actuation through the continued rotation of an element carried by the impression-cylinder of the second unit of the press.

11. In a multicolor offset press comprising two printing units each composed of a form-cylinder, a blanket-cylinder and an impression-cylinder, separate normally inoperative means for separating the blanket-cylinder from both form and impression-cylinders in each unit, and a timing mechanism positively controlled and simultaneously actuated by the direct movement of the separating means in the first unit to simultaneously place a part of the then normally inoperative separating means in the second unit in operative position for subsequent actuation at a predetermined point through the continued rotation of an element carried by the impression-cylinder of the second unit of the press.

12. In a multicolor press, a plurality of printing couples, separate normally inoperative means for throwing off the impression for each couple, and a normally inoperative timing mechanism comprising a latch relay

device controlled and actuated simultaneously by a direct connection with the first of said throw-off means to directly and simultaneously place a part of another then normally inoperative throw-off means in operative position.

13. In a multicolor press, a plurality of printing couples, separate normally inoperative means for throwing off the impression for each couple, and a normally inoperative timing mechanism comprising a latch relay device controlled and actuated simultaneously by a direct connection with the first of said throw-off means to directly and simultaneously place a part of another then normally inoperative throw-off means in operative position for subsequent actuation by the continued movement of the press.

14. In a multicolor press, a plurality of printing couples, separate normally inoperative means for throwing off the impression for each couple, and a normally inoperative timing mechanism comprising a latch relay device controlled and actuated simultaneously by a direct connection with the first of said throw-off means to directly and simultaneously place a part of another then normally inoperative throw-off means in operative position for subsequent actuation at a predetermined point by the continued movement of the press.

15. In a multicolor press, a plurality of printing couples, inking mechanisms therefor with separate means for throwing off same, independent normally inoperative means for separating each couple, and normally disconnected means controlled and simultaneously positioned by the tripping movement of each separating means for subsequently actuating the inker throw-off means in each couple.

16. In a multicolor press, a plurality of printing couples, inking mechanisms therefor with separate means for throwing off same, independent normally inoperative means for separating each couple, and means directly positioned and positively controlled by the tripping movement of each separating means for actuating the inker throw-off means in each couple in each cycle through the continued movement of the press.

17. In a multicolor press, a plurality of printing couples, inking mechanisms therefor with separate means for throwing off same, independent normally inoperative means for separating each couple, and means directly positioned and positively controlled by the tripping movement of each separating means for actuating at variably predetermined points the inker throw-off means in each couple.

18. In a multicolor press, a plurality of printing couples, inking mechanisms therefor with means for throwing off same, means for throwing off impression for the first cou-

ple, normally inoperative means for throwing off impression for another couple placed in operative position by said first impression throw-off means, and means controlled and placed in operative position by said impression throw-off means in each couple for operating its inker throw-off.

19. In a multicolor press, a plurality of printing couples, inking mechanisms therefor with means for throwing off same, means for throwing off impression for the first couple, normally inoperative means for throwing off impression for another couple placed in operative position by said first impression throw-off means, and means controlled and placed in operative position by said impression throw-off means in each couple for operating its inker throw-off at a predetermined point in the cycle after the impression is thrown off.

20. In a multicolor press, a plurality of printing couples, inking mechanisms therefor with means for throwing off same, means for throwing off impression for the first couple, normally inoperative means for throwing off impression for another couple placed in operative position by said first impression throw-off means, and means controlled and placed in operative position by said impression throw-off means in each couple for operating its inker throw-off at a predetermined point in the cycle after the impression is thrown off.

21. In a multicolor press, a plurality of printing couples, inking mechanisms therefor, separate normally inoperative means for throwing off same for each couple, means for throwing off impression for each couple having a connection with the inker throw-off to set the latter for operation, and means controlled and actuated by the impression throw-off of each couple to set its inker throw-off means and the impression throw-off for the next couple, in operative position operable through the continued movement of the press to sequentially actuate said inker throw-off means and said impression throw-off.

22. In a multicolor press, a plurality of printing couples, inking mechanisms therefor, separate normally inoperative means for throwing off same for each couple, means for throwing off impression for each couple having a connection with the inker throw-off to set the latter for operation, and means controlled and directly actuated by the impression throw-off of each couple to set its inker throw-off means and the impression throw-off for the next couple, in operative position operable through the continued movement of the press to sequentially actuate said inker throw-off means and said impression throw-off at a predetermined point in the cycle.

23. In a multicolor press, a plurality of

- printing couples, means for throwing off impression for each couple, inking mechanisms therefor, separate normally inoperative means for throwing off same for each couple normally inoperative but placed in operative position by its impression throw-off means when actuated thereafter to be sequentially actuated by the continued movement of the press, and a timing mechanism comprising 5 a latch relay device controlled and actuated by one of said throw-off means to position the impression throw-off means and inker throw-off in another couple for actuation by the continued movement of the press.
- 10 24. In a multicolor press, a plurality of printing couples, means for throwing off impression for each couple, inking mechanisms therefor, separate normally inoperative means for throwing off same for each couple normally inoperative but placed in operative position by its impression throw-off means when actuated thereafter to be sequentially actuated by the continued movement of the press, and a timing mechanism comprising 15 a latch relay device controlled and actuated by one of said throw-off means to position the impression throw-off means and inker throw-off in another couple for actuation by the continued movement of the press.
- 20 25. In a multicolor press, a plurality of printing couples, manually-inaugurated means for restoring the impression for each couple and a timing mechanism positively controlled and simultaneously actuated by the impression restoring means for one couple for automatically positioning in sequence the impression restoring means in another couple by the movement of the press.
- 25 26. In a multicolor press, a plurality of printing couples, manually-inaugurated means for restoring the impression for each couple and a timing mechanism positively controlled and simultaneously actuated by the impression restoring means for one couple for automatically positioning the impression restoring means in another couple for predeterminedly subsequent actuation by the continued movement of the press.
- 30 27. In a multicolor press, a plurality of printing couples each comprising a pair of rotary members, independent normally inoperative means for throwing off and throwing on the impression for each couple, means for positioning the impression throw-on means for the first couple, a timing mechanism positively controlled and simultaneously actuated by the tripping movement of the impression throw-on means for the first couple for automatically positioning the impression throw-on means in the next printing couple, and means operable through the continued movement of the press to actuate said several impression throw-on means in predetermined sequence.
- 35 28. In a multicolor press, a plurality of printing couples each comprising a pair of rotary members, independent normally inoperative means for throwing off and throwing on the impression for each couple, means for positioning the impression throw-on means for the first couple, a timing mechanism positively controlled and simultaneously actuated by the tripping movement of the impression throw-on means for the first couple for automatically and simultaneously positioning the impression throw-on means in the next printing couple, and means operable through the continued movement of the press to actuate said several impression throw-on means in predetermined sequence. 70
- 40 29. In a multicolor press, a plurality of printing couples each comprising a pair of rotary members, independent normally inoperative means for throwing off and throwing on the impression for each couple, means for positioning the impression throw-on means for the first couple, a timing mechanism comprising a latch relay device positively controlled and simultaneously actuated by the tripping movement of the impression throw-on means for the first couple for automatically and simultaneously positioning the impression throw-on means in the next printing couple, and automatic means operable through the continued movement of the press to actuate said several impression throw-on means in predetermined sequence. 85
- 45 30. In a multicolor press, a plurality of printing couples, separate normally inoperative means for throwing off and throwing on the impression for each couple, and a timing mechanism comprising a latch relay device controlled and simultaneously actuated by said throw-on means for one couple to automatically and simultaneously position the impression throw-on means for the next couple, both said impression throw-off and throw-on means being thereafter actuated in either direction in predetermined sequence in their respective cycles by a movable element in each couple operated through the continued movement of the press. 100
- 50 31. A two-color press comprising two printing units each having a pair of rotary printing members, independent means for throwing off and throwing on the impression for each couple normally inoperative and disconnected from each other, and a timing mechanism positively controlled and simultaneously actuated by the movements of said throw-off or throw-on means for one couple in either direction to automatically position the throw-off and throw-on means for the next couple. 115
- 55 32. A two-color press comprising two printing units each having a pair of rotary printing members, independent means for throwing off and throwing on the impression for each couple normally inoperative 120
- 60 65 33. A two-color press comprising two printing units each having a pair of rotary printing members, independent means for throwing off and throwing on the impression for each couple normally inoperative 125
- 65 34. A two-color press comprising two printing units each having a pair of rotary printing members, independent means for throwing off and throwing on the impression for each couple normally inoperative 130

and disconnected from each other, and a timing mechanism positively controlled and simultaneously actuated by the movements of said throw-off or throw-on means for one couple in either direction to automatically position the throw-off and throw-on means for the next couple, both said normally disconnected means being automatically actuated in either direction after being positioned through the continued movement of the press.

33. A two-color press comprising two printing units each having a pair of rotary printing members, independent means for throwing off and throwing on the impression for each couple normally inoperative and disconnected from each other, and a timing mechanism positively controlled and simultaneously actuated by the movements of said throw-off or throw-on means for one couple in either direction to automatically position the throw-off and throw-on means for the next couple, both said normally disconnected means being automatically actuated in either direction in predetermined sequence in their respective cycles after being positioned through the continued movement of the press.

34. A two-color offset press comprising two printing units each composed of a form-cylinder, a blanket-cylinder and an impression-cylinder, a sheet-transfer-cylinder in cooperative relation with each of the two impression-cylinders, the form cylinder in each unit being arranged substantially at right angles to its blanket and impression cylinders to provide a working space between the two form-cylinders above the impression-cylinders and transfer-cylinder.

35. A two-color offset press comprising two printing units each composed of a form-cylinder, a blanket-cylinder and an impression-cylinder, a sheet-transfer-cylinder in cooperative relation with each of the two impression cylinders all of equal diameters, the form cylinder in each unit being arranged substantially at right angles to its blanket and impression cylinders to provide a working space between the two form cylinders above the impression-cylinders and transfer-cylinder.

36. A two-color planographic offset press comprising two printing units each composed of a form-cylinder, a blanket-cylinder and an impression-cylinder, a sheet transfer-cylinder in cooperative relation with each

of the two impression cylinders the form-cylinder in each unit arranged substantially at right angles to its blanket and impression cylinders with the two units tilted at different angles from the base line of the press to provide a working space between the form-cylinder of one unit and the form and blanket cylinders of the other unit.

37. A two-color planographic offset press comprising two printing units each composed of a form-cylinder, a blanket-cylinder and an impression-cylinder, a sheet transfer-cylinder in cooperative relation with each of the two impression cylinders the form-cylinder in each unit arranged substantially at right angles to its blanket and impression cylinders with the two units tilted at different angles from the base line of the press to provide a working space between the form-cylinder of one unit and the form and blanket cylinders of the other unit above the two impression and transfer cylinders.

38. A two-color planographic offset press comprising two printing units each composed of a form-cylinder, a blanket cylinder and an impression-cylinder, inking mechanisms for the form-cylinders with means for throwing-off same, separate normally inoperative means for separating the blanket cylinder from both form and impression cylinders in each unit, a timing mechanism controlled and actuated by the separating means of the first unit to place in operative position the separating means of the second unit, and means for operating the inker-throw-off in each unit after its separating means has been actuated.

39. A two-color planographic offset press comprising two printing units each composed of a form-cylinder, a blanket cylinder and an impression-cylinder, inking mechanisms for the form-cylinders with means for throwing-off same, separate normally inoperative means for separating the blanket cylinder from both form and impression cylinders in each unit, a timing mechanism controlled and actuated by the separating means of the first unit to place in operative position the separating means of the second unit, and means for operating the inker-throw-off in each unit at a predetermined point in the cycle after its separating means has been actuated.
